UNITED STATES PATENT OFFICE.

CHRISTIAN MARTIN HANSEN, OF MJONDALEN, NORWAY, ASSIGNOR TO A/S. THUNES MEK. VERKSTED, OF SKOYEN, NEAR OSLO, NORWAY.

PRIMARY STRAINER FOR CELLULOSE, WOOD PULP, ETC.

Application filed November 18, 1926, Serial No. 149,224, and in Norway November 26, 1925.

The most usually employed knot catchers for cellulose are only to a small degree lenient in their treatment of the knots. Particularly this is true of the types in which 5 the knots are collected in the interior of rotating drums.

By the present invention the inventor has succeeded in providing an apparatus for continuously removing the knots in the cellulose without the latter being in any way injured by a too hard treatment, and at the same time the knots are nevertheless, before they are removed from the machine, washed quite clean from adhering cellulose fibres.

15 Further the new apparatus, in addition to its simple construction, possesses also the great advantage that nothing of the height of the pulp level is lost. The machine is arranged directly in the horizontal pulp 20 channel and therefore, both regarding floor area and building height, it results in a space-saving solution of the problem, and at the same time its expenditure of power is quite minimal, because the same is restricted to the power required for moving the grating slowly against the pulp stream.

The drawing illustrates diagrammatically an embodiment of the invention, Figure 1 being a longitudinal section and Figure 2 a cross section of the primary or coarse-strainer apparatus (knot-catcher). The catching gratings 2 are attached to a shaft 3 rotating transversely to the pulp channel 1. These gratings comprise a great number 35 of parallelly attached bars spaced suitably apart in order to catch the knots, whereas the cellulose is allowed to pass through without any hindrance. Obviously nothing prevents the use of other means for straining the pulp than the bar-shaped gratings here indicated. Thus the use of for instance a perforated or slotted plate may be suggested. The grate-bars in the embodiment here shown are so bent that the caught knots are taken 45 along upwards above the level of the cellulose pulp, where it is loosened from the bars and simultaneously washed clean from fibres by a strong oscillating rinsing jet from the pipe 6. During the further upward movement of the grating the knots will fall down 50 against the shaft and be collected in the

channel-shaped flow between the fastening ribs of the bars. When the grating arrives at its uppermost position, this channel is axially swept by a strong rinsing jet from 55 the nozzle 4. This water jet transports the collected and cleansed knots out to the side, where it is collected by the funnel 5 and conducted away.

In order to prevent any pulp from passing 60 the apparatus unstrained, the channel is provided with a recessed portion corresponding to the outer moving radius of the gratings. The recessed portion is made so large that all the pulp passing through the supply 65 channel must pass through at least one grating.

Claims.

1. Coarse-straining apparatus for sorting cellulose, wood pulp and the like comprising 70 a pulp channel, a scooping wheel, the shaft of which is arranged transversely to the pulp channel and the scoops of which are made as coarse strains or gratings corresponding approximately to the cross section 75 of the pulp channel, so that the scoops during their movement through the pulp in the pulp channel sweep with them knots and impurities but allow the fine pulp to pass.

2. Apparatus as set forth in claim 1, 80 characterized by this that transversely to the pulp channel a rinsing pipe is arranged which rinses the knots inwardly towards the shaft, where they are collected in the channel-shaped portion between two scoops. 85

3. Apparatus as set forth in claim 1, characterized by this that at one side of the scooping wheel near the shaft a rinsing nozzle is arranged which sweeps the knots to the side out from the channel between 90 two scoops, when the latter are in their uppermost position or approximately so.

4. Apparatus as set forth in claim 1, characterized by this that the pulp channel, at the place where the scooping wheel is 95 arranged, is provided with a recessed portion following the largest radius of the scoops.

In testimony whereof I have signed my name to this specification.

CHRISTIAN MARTIN HANSEN.
